UNITED STATES PATENT OFFICE

2,549,677

ROTARY WASHING MACHINE

Clinton Frank Egerton, New York, N. Y.

Application January 15, 1947, Serial No. 722,239

4 Claims. (Cl. 68—4)

1

This invention relates to washing machines of the rotary type, and more particularly, to a rotary washing machine designed for attachment to a sink, laundry tub, or the like.

The primary object of the invention is to provide a washing machine of this type which may be mounted in a deep-welled sink or laundry tub, and which will effectively wash either fabric materials or dishes, pans, and similar articles.

It is a further important object of the invention to provide a machine of this type which will both wash and rinse dishes or clothes, and which will be additionally operable as a drier of clothes or other fabric material, acting on them in such manner as to draw a considerable part of the water from them, leaving them in a substantially dry condition.

It is proposed to carry out these objects by means of a machine which is of novel construction, adapting it for manufacture at considerably less cost than rotary washing machines now in use, and which may be mounted in already installed sinks or tubs of conventional formation.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings:

Figure 1 is a transverse sectional view through a sink in which a rotary washing machine constructed in accordance with the invention is mounted, in which adapter and power means mounted below the sink are shown in elevation, an impeller mounted in the sink compartment appears in elevation with parts broken away, and a dish rack attachment is shown partly in section.

Figure 2 is a vertical sectional view through the device, with dish rack attachment, mounted in a sink.

Figure 3 is a perspective view of the impeller embodied in the invention.

Figure 4 is a perspective view of the adapter embodied in the invention.

Figure 5 is a perspective view of the valve means embodied in the invention.

Figure 6 is a bottom plan view of drive means embodied in the invention.

Figure 7 is a side elevational view of valve and power control means.

2

Figure 8 is a vertical sectional view of a clothes rack attachment, mounted on the impeller.

Referring to the drawing in detail, the character reference numeral 5 designates the sink compartment of a standard type of deep-welled domestic laundry or kitchen sink, in which my rotary type washing machine is adapted to be mounted.

In the bottom of the sink compartment 5 is seated a circular stationary supporting plate 6 having a concentric opening 7, the plate being provided with a flat peripheral supporting edge or flange 8, and being slightly arched between the flange 8 and opening 7. Additionally, the supporting plate 6 is provided with a plurality of large openings 8' through which water is drained off after use of the washer.

To the supporting plate 6 and around the opening 7 is secured the ballbearing 9 carrying the rotatable impeller, which I have designated generally by the character reference numeral 10. The impeller 10 is integrally formed, with an axially disposed shaft 11 that is open at its upper end, and has a cylindrical bore, that terminates adjacent the base 12 of the shaft, providing an overflow drain. The base 12 is of solid formation, of reduced circumference, and is externally threaded. At the lower end of the bore is provided the overflow drain opening 13, of which there may be one or more, as desired.

As may be seen by reference to Figure 2, the impeller 10 is mounted so as to extend partly above and partly below the bottom of the sink compartment 5, the outer wall of the shaft 11 having an annular shoulder 14 that supports the impeller 10 for rotation upon the bearing 9.

Integral with the shaft 11 are blades or vanes 15 that are also integral with the annular impeller ring 16, being extended outwardly from the shaft 11 to the ring 16. As may be clearly seen by reference to Figure 3, each blade 15 is substantially scoop-shaped, being formed with deep-curved upper and lower edges that extend between the shaft 11 and ring 16, and with a shallow-cupped blade surface between its upper and lower edges, the upper edge being positioned rearward of the lower edge, when considering the direction of their rotation. The ring 16 is formed with a rippled lower edge, the widened portions forming side walls 18 of the blades 15 that prevent water from escaping from the cupped surfaces of the blades during their rotation.

Extending above the blades 15 is the upper end portion 19 of the shaft 11 which is tapered and of hexagonal conformation, as shown in Figure 3,

The lower portion of the shaft 11 rotates in an adapter, which I have designated generally by the character reference numeral 20, that is mounted against the underside of the bottom of the sink compartment 5. The adapter 20 may be cast integral, with a substantially cylindrical recess 21 having a flat relatively wide upper end edge 22, and a centrally disposed up-standing sleeve portion 23, that is tapering in form, and is provided with a plurality of spaced vertical ribs 24.

As may be seen by reference to Figure 4, the sleeve portion 23 extends above the upper end edge 22, this construction being used so that the sleeve portion may be projected upwardly through the drain orifice of the sink compartment 5. The adapter 20 is provided throughout with a bore 25 that is made concentric with the drain orifice of the sink compartment 5 by the centering effect of the tapered sleeve portion 23 in being positioned through the drain orifice.

The adapter 20 is further formed with a main drain opening 26 in the bottom of the recess 21 that communicates with a chamber 27, there being an exterior opening 28 in the side wall of the adapter that also communicates with the chamber, and into which is threaded the upper end of a drain pipe 29. An interiorly disposed overflow drain opening 29' into the chamber 27 is also provided in the adapter, and communicates between the chamber 27 and the overflow drain openings 13 of the shaft 11.

As may be clearly seen by reference to Figure 2, the bottom of the recess 21 is formed with a relatively shallow annular groove 30 that accommodates for slidable rotation an annular valve closure 31. Leaf springs 32 have one end secured to the upper surface of the valve closure 31 and have their other ends inclined upwardly so as to engage the underside of the bottom of the sink compartment 5, thereby exerting downward pressure on the valve closure 31, so as to hold it snugly in its groove 30.

Having one end secured to the valve closure 31 is a flexible operating rod 33 that is extended through an opening in the wall of the recess 21, the other end being connected to an arm 34 that is operable by a handle 35 mounted on a panel 36 in the wall of the sink cabinet.

A length of tubing 37 has one end fixedly attached to a suitable bracket on the panel 36, the other end being fixedly attached to the adapter 20, and the rod 33 is slidable through the tubing.

When it is desired to drain off the water in the sink, semi-rotation of the handle 35 in one direction causes the rod 33 to slidably move the valve closure 31 in the groove 30, causing the valve opening 38 in the valve closure to register with the main drain opening 26 of the adapter, as may be clearly seen by reference to Figure 2. Semi-rotation of the handle 35 in an opposite direction results in closing of the main drain opening 26.

In mounting the washer in a sink, the sleeve portion 23 of the adapter 20 is extended upwardly through the drain orifice of the sink compartment, the upper edge of the sleeve portion abutting against the plate 6. Spacers 39 on the plate 6 that are disposed around the opening 7 of the plate engage the sleeve portion 23 between the ribs 24, thereby more firmly holding the plate in its stationary position.

The shaft 11 of the impeller 10 is then positioned through the bore 25 of the adapter 20,

the threaded lower end 12 of the shaft projecting below the adapter. A pulley 40 having an interiorly threaded axially disposed opening is threaded onto the lower end 12, and is provided with an annular flange 41 to which is secured a ballbearing 42 that bears in a suitable recess at the lower end of the adapter.

Threading of the pulley 40 onto the lower end 12 of the shaft 11 will result in the adapter 20 being forced into tight engagement with the underside of the sink, there being provided a suitable annular gasket 43 that is interposed between the upper end edge 22 of the adapter and the bottom surface of the sink. The effect of threading together the impeller shaft 11 and pulley 40 thus clamps the entire device securely in position.

From an electrical motor 44, that is operable by a switch 45 on the panel 36, and which may be secured to a vertical supporting surface 46 such as a wall, rotary movement is transmitted to the impeller 10 by means of a belt 47 passing around the pulley 48 on the motor and around the pulley 40 threaded onto the shaft 11. A roller 48' that is mounted on the adapter prevents the torque of the power means from twisting the adapter or plate 6 during operation. In mounting the device, the adapter is positioned so that the roller 48' will take the slack out of the belt 47.

My device is further provided with a stationary dish rack that is proportioned to fit over the impeller 10 but which is at no point in contact with the impeller. This rack is freely perforated throughout, as at 49, so that water may freely circulate therethrough, and has ribs or projections 50 that are adapted to retain dishes and the like in an efficient arrangement for washing.

By referring to Figure 8, it will be seen that alternative to the dish rack, a clothes rack is also provided, that has a hollow tapered hexagonal dome portion 51 that engages upper end portion 19 of the impeller, this being the only portion of the clothes rack that is engaged. By reason of this construction, the clothes rack is rotatable with the impeller 10. The clothes rack is also provided with a plurality of large perforations 52 through which water may freely circulate, and with a cylindrical clothes-retaining side wall 53.

In operation of my device with the dish rack attachment, the rapidly rotating blades 15 are adapted to scoop up the water and to force it upwardly in a continual swirling motion through the perforations 49 of the rack, thereby effectively cleaning the dishes in a short time.

In washing clothes, the blades act similarly, and in addition, the clothes rack itself rotates with the blades as hereinbefore described, the combined action resulting in a swirling turbulent water motion that efficiently dislodges the dirt.

To rinse, the water is drained off, by opening the valve as hereinbefore described. When this is done, the water drains through the openings 8' in the plate 1, through the drain orifice of the sink (by passing through the openings formed by the ribs 24 between the edge of the sink drain orifice and wall of the sleeve portion 23) and through the registering valve and main drain openings 38 and 26 respectively. Clear water is then run into the sink, and the machine again started.

To damp-dry the clothes after rinsing, the rinse water is drained off, and the machine again started. This results in the clothes being whirled

rapidly in the clothes rack, the water in the fabric being drawn by centrifugal force through the perforations 52 in the side wall 53 of the rack. Concurrently, the air agitated by the whirling of the clothes has a cooperating drying effect.

During washing operations, it is understood that a cover may be provided over the sink. Further, it is pointed out that it is possible, if desired, to provide a detachable basin that may be fitted into the sink over the device when the device is not in use, in order to permit ordinary use of the sink.

What is claimed is:

1. A washing machine for mounting in a sink compartment including a circular stationary supporting plate provided with drain perforations, a rotatable impeller mounted above the supporting plate, the impeller comprising an axially disposed shaft of hollow formation, said shaft having spaced inlet and outlet openings communicating with the interior and exterior of the compartment respectively to provide an overflow drain, and a plurality of water-disturbing blades integral with the shaft, a stationary adapter having a bore, the shaft being rotatable in said bore, the adapter being provided with a main drain communicating with the sink compartment, a valve closure slideable over said drain, operating means for the valve closure, drive means operatively connected to the shaft for rotating the shaft, and a stationary dish rack mountable over the impeller and comprising a perforated housing proportioned to cover the sides and top portion of the impeller and wholly spaced from the impeller, said housing being formed with a plurality of dish-engaging projections.

2. A washing machine for mounting in a sink compartment, including a circular stationary supporting plate elevated at its center and inclined downwardly towards the edge thereof, said supporting plate having drain openings, a rotatable impeller mounted above the supporting plate and including a vertical hollow shaft open at its upper end in communication with the interior of the compartment and open at its lower end in communication with the exterior of the compartment to provide a drain, impeller blades secured to the shaft, a dish supporting rack mounted above the rotatable impeller and housing said impeller, and ribs extending upwardly from the dish rack against which dishes are held, said rack having openings adjacent to the ribs whereby fluid from the impeller is forced upwardly between dishes supported on the rack.

3. A washing machine for mounting in a sink compartment, including a circular stationary supporting plate provided with drain perforations, a rotatable impeller mounted above the supporting plate, the impeller comprising an axially disposed shaft of hollow formation, said

shaft having spaced inlet and outlet openings communicating with the interior and exterior of the compartment respectively to provide an overflow drain, a plurality of water-disturbing blades integral with the shaft, and a non-circular end portion on the shaft, a stationary adapter having a bore, the shaft being rotatable in said bore, the adapter being provided with a main drain communicating with the sink compartment, a valve closure slideable over said drain, operating means for the valve closure, drive means operatively connected to the shaft for rotating the shaft, and a clothes rack including a non-circular dome portion receiving the corresponding portion of the shaft for rotation of the rack with the shaft, a perforated bottom portion rigid with and surrounding said dome portion, said bottom portion overlying the impeller blades, and a perforated side wall rigid with and extending upwardly from the periphery of said bottom portion.

4. A washing machine for mounting in a sink compartment, including a circular stationary supporting plate elevated at its center and inclined downwardly towards the edge thereof, said supporting plate having drain openings, a rotatable impeller mounted above the supporting plate and including a vertical hollow shaft open at its upper end in communication with the interior of the compartment and open at its lower end in communication with the exterior of the compartment to provide a drain, impeller blades secured to the shaft, and a non-circular end portion of the shaft, a clothes rack mounted above the impeller and housing said impeller, said rack including a non-circular dome portion engageable with the non-circular portion of the impeller for rotation of the rack with the impeller, a perforated bottom portion rigid with and surrounding said dome portion, said bottom portion overlying the impeller blades, and a perforated side wall rigid with and extending upwardly from the periphery of said bottom portion, and drive means for the impeller.
